INVENTOR.

UNITED STATES PATENT OFFICE.

GEORGE E. NERNEY, OF ATTLEBORO, MASSACHUSETTS.

DESIGN FOR A BADGE OR JEWEL.

41,180.

Specification for Design.

Patented Feb. 21, 1911.

Application filed December 30, 1910. Serial No. 600,186. Term of patent 7 years.

To all whom it may concern:

Be it known that I, GEORGE E. NERNEY, a citizen of the United States, residing at Attleboro, in the county of Bristol and State of Massachusetts, have invented a new, original, and ornamental Design for a Badge or Jewel, of which the following is a specification, reference being had to the accompanying drawing, forming part thereof.

The figure is a plan view of a badge or jewel, showing my new design.

I claim:

The ornamental design for a badge or jewel as shown.

GEORGE E. NERNEY.
